FRANK C. AXTELL, OF SOUTH PASADENA, CALIFORNIA, ASSIGNOR TO AXTELL RESEARCH LABORATORIES, INC., OF LOS ANGELES, CALIFORNIA, A CORPORATION OF CALIFORNIA.

PROCESS FOR THE REFINING OF PETROLEUM FRACTION.

Application filed September 24, 1925. Serial No. 58,327.

As is well known to those skilled in the art, dehydrated crude petroleum is subjected to distillation in order to separate it into constituent commercial products, such as 5 gasoline, engine distillate, kerosene, fuel oil, lubricating stock, etc. Some of these distillates, such as gasoline, kerosene, etc., are then subjected to a refining process by means of which certain impurities which 10 they contain, such as sulphur compounds, nitrogenous bases, acids, etc., are removed, some of the refined products being subjected to a final distillation.

In refining such distillates, it is usually 15 the custom to subject the same to the action of an oxidizing agent, the object being the oxidation of the sulphur compounds and other impurities contained therein, rendering the same soluble in more or less highly 20 concentrated sulphuric acid when the distillates are treated therewith subsequent to such oxidizing treatment. With the oxidizing agents usually employed, great difficulty is experienced in controlling the action 25 thereof, as not only the impurities are oxidized, but valuable hydrocarbon constituents of such distillates are also attacked. This results not only in a direct loss thereof, but 30 in an instability such that the petroleum products thus made are characterized by the fact that they become yellow upon standing or when subjected to the action of air and light, and possess other objectionable 35 properties.

The above observations are particularly true as regards the distillates made from asphaltic base petroleums or from petroleums of mixed asphaltic and paraffin base. As is well known to those skilled in the art, 40 distillates from these crude petroleums are characterized by a high degree of instability, and it is almost impossible to refine these distillates in such way as to insure colorless, stable products.

With these facts in view, it is evident that, 45 in order to successfully oxidize the impurities contained in such distillates, an oxidizing agent which will not attack the valued hydrocarbons themselves should be employed; and I find that persulphuric and Caro's acid, when properly used, possess this 50 property.

The figure may be regarded as a diagram

or flow-sheet illustrating one series of steps in which my process is employed, the most 55 essential novel steps being indicated by double-line rectangles; and steps which may be omitted when gasoline is treated being enclosed in dotted lines.

In carrying out this invention I prefer to 60 proceed as follows: For instance, for the production of a fine illuminating oil from California distillate, I prefer to take a "cut" having an initial boiling point of about 300° F., and a "dry" (end) point of about 510° F., 65 with a gravity of about 40° to 41° at 60° F. by the American Petroleum Institute hydrometer. The first preliminary treatment in my process may consist in subjecting such a distillate to treatment with dilute sulphuric 70 acid containing about 5 per cent H_2SO_4 , using about twenty pounds of this dilute acid for each barrel of the distillate treated. The oil and acid are to be very thoroughly agitated, so that the acid assumes a very finely 75 divided state, and the agitation is preferably continued for from about thirty minutes to one hour, at the end of which time the acid is allowed to settle under the action of gravity and is separated from the distillate. The object of this treatment is the removal of certain basic compounds which are present in the distillate and which combine with the sulphuric acid and are soluble 80 therein.

After this treatment, the distillate may then advantageously be washed with, say, one charge of water amounting to about one-fourth the amount of the distillate, being 85 thoroughly agitated therewith and permitted to settle and then separated therefrom.

The distillate is next treated with a solution consisting of about one pound of a caustic alkali, preferably sodium hydroxide, dissolved in about three pounds of water, for 90 each barrel of distillate treated. This solution is to be very thoroughly agitated with the distillate, preferably for about an hour. At the end of this time, about one gallon of water may advantageously be added for each 100 barrel of distillate treated, the mixture being then again agitated for about five minutes, after which the aqueous solution is permitted to settle and is separated from the distillate. The latter may then be washed with 105 two or three successive charges of water,

each charge amounting to from one-fourth to one-half the volume of the distillate treated, each charge being allowed to settle and separated from the oil. The withdrawn alkaline solution contains, in the form of soaps, the naphthenic and other organic acids which were present in the oil, and these soaps may, if desired, be decomposed and the acids recovered therefrom by treatment with 10 a mineral acid, such as sulphuric acid, in the well-known manner.

Regarding the foregoing steps as preliminary and as in part optional, the oil is now ready for my special oxidizing treatment, 15 which is carried out, as follows:

My preferred oxidizing agent may be prepared by dissolving a persulphate, such as persulphate of sodium or of potassium, in concentrated sulphuric acid,—the degree of concentration of the sulphuric acid depending upon the nature of the distillate to be treated, the amount and character of the impurities which it may have been found to contain, and the temperature at which the dissolving and incidental reactions take place. 20 When the persulphate is dissolved in sulphuric acid, persulphuric acid is liberated and exists as such in the sulphuric acid solution, being slowly converted to Caro's acid 25 (H_2SO_5) upon standing.

For the treatment of distillate for the production of an illuminating oil, I prefer to dissolve, at ordinary "room" temperature, about one pound of sodium or potassium 30 persulphate in ten pounds of sulphuric acid containing from 97.5 to 98 per cent H_2SO_4 ; and, when solution is complete and the mixture has stood for about one hour at about 20° C., I add the resultant solution, in substantially the amount named, to each barrel 35 of distillate treated. The mixture, containing persulphuric acid and Caro's acid solution and distillate, is then very thoroughly agitated for about one hour in such manner 40 that the oxidizing agent is very completely broken up and is kept in a state of fine subdivision and suspension in the oil during 45 the period of treatment. In this connection, I mention that the arrangement of the 50 treating apparatus should be such that air, other than that normally contained in the apparatus, is not permitted access thereto, it having been found that if relatively large 55 quantities of air are drawn into the mixture, as through the action of the agitator, the moisture contained in such air has a strong tendency deleteriously to affect, by dilution of the acid mixture the progress and result of the reaction.

60 The advantages of the use of this oxidizing agent include the facts that not only are the impurities, such as sulphur and other compounds which are contained in the oil, rendered soluble in the sulphuric acid, but 65 they are also dissolved by the latter as rapid-

ly as they are oxidized; and, further, the valuable hydrocarbons apparently are not in the least affected.

After the foregoing treatment is completed, the acid sludge being permitted to settle and separated from the distillate, the latter may be treated with a fresh charge or charges of sulphuric acid, this acid being optionally of substantially the same strength as that which was employed in the oxidation; but, in these latter charges, no persulphuric acid or persulphates are employed, the purpose of these final charges being to insure that all oxidized compounds are removed from the distillates by solution in such sulphuric acid. For the purpose indicated, this charge or these charges of acid, used in acid-washing, are also to be very thoroughly dispersed in a very finely divided state and kept in suspension in the oil for about thirty minutes each, at the end of which time they are permitted to settle and are separated; and the acid-washed oil or distillate may then be very thoroughly water-washed, as with at least three charges of 80 water, each amounting in volume to about one-half that of the volume of the oil; or an equivalent quantity of water may be sprayed through the oil in a well-known manner. At the end of these washing operations, or 85 their equivalents, the oil should be practically colorless, and should remain so.

In case traces of acid are objectionable, the next step may consist in treating the oil with a dilute alkaline solution for the 90 neutralization of any traces of acid which it may contain; and for this purpose a solution of either sodium or potassium hydrate, or sodium or potassium carbonate, may be employed, the strength of such solution being preferably of from three to five per cent of sodium or potassium hydrate or an equivalent quantity of the alkaline carbonates, used in quantity amounting to from one-fourth to one-half pound of the dry potassium 95 or sodium hydrate, or an equivalent quantity of the carbonates, for each barrel of the distillate treated. This alkaline solution is preferably to be very thoroughly agitated with the oil for about thirty minutes, at the end of which time the alkaline 105 solution is allowed to settle and is separated from the oil; and the latter may then be thoroughly washed with water, substantially 110 as before, for the removal of the traces 115 of alkali which it may contain.

For the finest results, oils treated as above may advantageously be redistilled, for which purpose a still having a large and efficient dephlegmator is desirable, the oil 120 being preferably distilled with steam therefrom. In the production of an illuminating oil, it is found advantageous to avoid the use of superheated steam for this purpose, using only saturated steam, which may ob-

tain some superheat in passing through the still. It is also found advantageous, in the distillation of this illuminating oil to keep the temperature of the vapors at the top 5 of the dephlegmator below 350° F., that is, the temperature should not at any time exceed 350° F. at this point; and, as a rule, the temperature of the oil in the body of the still need not exceed about 420° F.

10 The steam distillate may be separated, in a well-known manner, from the water which accompanies it and may then be permitted to stand quietly in a proper receptacle until the emulsified water separates therefrom,— 15 leaving the oil in a perfectly transparent, colorless condition, ready for the market.

An illuminating oil made from California distillate by the process above described may contain from about 0.005 to 0.015 per cent of 20 sulphur, and may have an A. P. I. gravity of about 40.5°. It should be perfectly colorless, and burn indefinitely without the production of a smoky flame.

The method above described for the production of an illuminating oil may, with the necessary modifications, be employed for the purification and stabilization of other distillates, such as gasoline, engine distillates, etc; but in treating light distillates, the 25 quantity of persulphate in sulphuric acid employed, and the strength of the sulphuric acid must be adjusted to meet the conditions. For instance, for treating a gasoline distillate, it is usually sufficient to agitate such 30 distillate with from about three to five pounds of 95 per cent sulphuric acid in which from one-fourth to one-half a pound of sodium or potassium persulphate has been dissolved (with formation of a corresponding quantity of persulphuric acid and 35 Caro's acid therein) per barrel of distillate; and, as a rule, it is not necessary to follow this treatment with further acid treatment, the distillate, after separation of the acid 40 sludge and thorough washing with water, being merely neutralized with about one-fourth pound of sodium hydrate dissolved 45 in about nineteen pounds of water, per barrel, and then being thoroughly washed in 50 the well-known manner.

Engine distillate is treated in the same general way; but the quantity of persulphate-sulphuric acid oxidizing agent required may slightly exceed that which is required for a gasoline distillate.

55

This process is also applicable to the treatment of crude lubricating stock. In a general way, the treatment is the same as that described above, but the strength of the sulphuric acid employed as vehicle and solvent, and the amount of persulphate dissolved therein, must be determined by test, by reason of the fact that lubricating oils differ so greatly as regards the chemical 60 constitution of the hydrocarbons which they contain that a formula applicable to the treatment of all lubricating oils cannot be given.

This process, referred to as especially suitable for use in the refining of California 70 oils, is also valuable in its application to the refining of oils containing more paraffins; but the quantity of the described reagent acid mixture required may, in the latter case, be considerably less than is necessary 75 in the refining of distillates from asphaltic base oils.

The novel reagent acid mixtures above mentioned are used, substantially as described, in all embodiments of my invention, only the preliminary treatment or the washing or neutralizing or distilling steps being included or omitted or varied according to the hydrocarbon treated and the product desired. No novel apparatus being 80 required, installations suitable for the practice of my invention can be provided at very moderate cost, and the same installation can be used in the production of a wide variety of superior products, substantially free from 85 sulphur.

I claim as my invention:

In refining petroleum oils, the treatment thereof with sulphuric acid solutions of per-sulphuric acid and Caro's acid, substantially 90 as herein set forth and described.

In testimony whereof, I have hereunto set my hand at Los Angeles, California, this 16th day of September, 1925.

FRANK C. AXTELL.
